UNITED STATES PATENT OFFICE

1,980,154

MEANS FOR CONNECTING STRIPS OF
SHEET METAL

James R. Coe, Watertown, Conn., assignor to
The American Brass Company, Waterbury,
Conn., a corporation of Connecticut

Original application September 28, 1932, Serial
No. 635,215, now Patent No. 1,928,409, dated
September 26, 1933. Divided and this applica-
tion March 23, 1933, Serial No. 662,272

2 Claims. (Cl. 287—64)

This invention relates to new and useful im-
provements in means for connecting the end
portions of strip metal and to the method of
forming such connection.

5 An object of the invention is to provide a
simple and inexpensive connection for connect-
ing the forward end of one metal strip to the
rearward end of a second metal strip.

Another object is to provide an improved
10 method whereby one end of a metal strip may
be easily and quickly attached to an end of a
second metal strip, and is especially adapted for
connecting such strips when they are used in a
continuous operation such as a continuous an-
15 nealing operation.

Other objects and advantages will become ap-
parent from a consideration of the following
detailed description taken in connection with
the accompanying drawing wherein a satisfac-
20 tory embodiment of the invention is shown.
However, it will be understood that the invention
is not limited to the details disclosed but
includes all such variations and modifications
as fall within the spirit of the invention and the
25 scope of the appended claims.

In the drawing:

Fig. 1 is a top plan view showing a pair of
sheet metal strips associated with a punch and
die by means of which the strips are to be con-
30 nected;

Fig. 2 is a sectional view through Fig. 1, and
showing the manner in which the strips are
treated by the punch and die;

Fig. 3 is a top plan view showing the end por-
35 tions of two strips connected according to the
present invention; and

Fig. 4 is a detail sectional view taken substan-
tially along the line 4—4 of Fig. 3.

The present application is a division of my
40 prior application, Serial Number 635,215, filed
September 28, 1932, and while the joint and
method of the present case are useful in the
furnace and method set forth in the above en-
titled application, they are not restricted to
45 such use. According to the method of the pres-
ent invention a punch press (not shown) is
equipped with a desired number of punching
or lancing tools 5 preferably arranged in a row
50 and in spaced relation to one another. Prefer-
ably these tools 5 are spaced approximately
three inches apart and extend for the length
of a die bed and press plate and each tool com-
prises a circular shearing punch from which
55 a certain portion of the cutting edge is omitted
or removed by filing as indicated at 6 in Fig.

2. The omitting or removing of this portion of
the punch results in the same having its lower
surface inclined as shown, the said surface in-
clining from one edge 18 toward its portion 6.

These punches or tools cooperate with circu-
lar shearing dies 7 mounted in any suitable bed
plate 8, and a certain portion of the cutting edge
19 of each die is omitted or removed as at 9.

The amount cut away is preferably less than a
semi-circle so that the portion of the strip cut 60
will be more than a semi-circle as indicated in
Fig. 3. Tools 5 and dies 7 are used to connect
the forward or front end of one strip of metal
to an end of a second strip of metal whereby
movement of the said second strip of metal will 65

be imparted to the first strip and the second
strip may be used for threading the first strip
through a furnace or other device. In the draw-
ing, there are shown portions of strips 10 and 11
connected according to the present invention. 70

To connect these ends, portion 11 is disposed on
portion 10 below the punches or tools 5 and these
are operated downwardly to partially lance and
press downwardly portions 12 of the strip 10 75

and portions 13 of the strip 11. Thus holes 80
or openings 15 and 16 are formed in the strips
10 and 11 respectively and the ears or portions
12 and 13 are attached to their respective strips
at one edge of the openings 15 and 16 respec- 85

tively as indicated at 14 by strips less than a
semi-circle in width, and it will also be noted
the upper ears or portions 13 are carried down-
wardly through the openings 15 in the lower
strip 10.

This is because the punches and dies are cut 90
away as at 6 and 9 so the depressed portions 12
and 13 will remain connected as by neck por-
tions 14 with the respective strips from which
they have been pressed. After the strip portions
12 and 13 have been lanced and pressed as de- 95

scribed the strip 10 and the strip 11 are moved
relatively. This relative movement may be ac-
complished by drawing the strips in opposite di-
rections or by maintaining one strip stationary
and moving the other longitudinally in a direc- 100

tion off the strip being held stationary. If the
strip 10, as shown in Fig. 2, is moved toward the
right relative to the strip 11 then the downward-
ly depressed portion 13 of strip 11 will be dis-
posed through but out of registry with the open- 105

ing 15 formed in the strip 10, or that is, the edge
of opening 15 will be on top of the ears or
downwardly bent portions 13 as shown in Fig.

4. In other words, the strips will be connected
as suggested since as the strip 10 moves for- 110

wardly or to the right in Fig. 2, relative to the strip 11, the extreme end portion 17 of the strip 10 will slide to a position over the depressed portions 13 as best shown in Fig. 4. That is, 5 the depressed portion 13 of strip 11 forms a sort of hook which engages in the opening 15 directly under it. It will be understood that the desired number of these punchings may be used and that the number will vary with the width of the strips being connected. When one strip is to be 10 used to draw another along it is preferred that at least two spaced portions of the strips be pressed through since when the strips are connected at two points any substantial relative turning movement between the strips will be prevented. 15

From the foregoing it will be appreciated that by the method of the present invention the end portions of a pair of strips may be easily and 20 quickly connected. It is but necessary to dispose the end portions of the strips in over-lapping relationship and to then operate the punches 5 to lance and press downwardly the ears or cut out portions of the two strips whereby the partially lanced portions of one strip extend through 25 the other strip. When a pair of strips are connected by the joint of the present invention they cannot be separated, except by shifting them relatively to bring their depressed portions 12 and 13 into complete registry after which the strips may be shifted relatively vertically to 30 disconnect them. However, while the strips are positioned as shown in Figs. 3 and 4 there is no casual movement which will separate them since they must be manipulated into a particular 35 position before they can be separated because as indicated in Fig. 3 the front edges 20 of the openings 15 have passed beyond the widest part of the ears 13 indicated by line 20 on to the narrower neck or connecting portion 14 so the ears 40 13 cannot pass upwardly through the openings

15. Or in other words the strip 10 cannot drop away from the strip 11. When connected the end portion 17 of strip 10 overlaps the depressed portions 13 of strip 11 as clearly shown in Figs. 3 and 4 and since portions 13 are inclined or hooked a wedging action will be obtained when the strips are moved relatively longitudinally and any longitudinal pull between the strips will tend to more securely lock them together. 80

Having thus set forth the nature of my invention, what I claim is:

1. In combination, two superimposed strips, said strips having similar portions partially lanced and pressed therefrom and providing openings in the strips and similarly extending portions at the same sides of the strips and each connected with its strip by a neck portion of less width than the pressed portion, and the pressed portion of one strip extending through the opening in the other strip to the side of said other strip at which the pressed portion of the latter is located and with the edge of the opening of said other strip engaging the neck of that pressed portion extending through said opening whereby said strips are connected. 90

2. In combination, two superimposed strips of sheet metal both of which have portions of substantially the same size and shape partially lanced therefrom and both pressed laterally from the planes of the strips in the same direction to 105 provide openings in the strips, the lanced portions being connected to the strips by neck portions of less width than the lanced portions, the lanced portion of one strip being passed through the opening of the other strip, and the openings 110 being out of alignment with the edges of the second opening opposite to the neck on that strip engaging the neck of the lanced portion of the first strip to connect the two together. 100
